UNITED STATES PATENT OFFICE.

ALBERT A. AKE, OF KANSAS CITY, MISSOURI.

AUTOMATIC AIR AND WATER PROPELLER.

1,330,296.

Specification of Letters Patent. Patented Feb. 10, 1920.

Application filed May 24, 1918. Serial No. 236,285.

To all whom it may concern:

Be it known that I, ALBERT A. AKE, a citizen of the United States, residing at Kansas City, in the county of Jackson and State of Missouri, have invented certain new and useful Improvements in Automatic Air and Water Propellers, of which the following is a specification.

My invention relates to propellers, and my object is to provide a new and useful device of this character which can operate equally as well in air or water and be employed to advantage in propelling aeroplanes, vessels, etc. A further object is to provide a device of this character which may be used as a windmill for operating pumps and other machinery or as a water wheel for operating grist mills, etc.

Other advantages will hereinafter be pointed out and in order that the invention may be fully understood, reference will now be made to the accompanying drawings, in which:

Figure 1 is a side elevation of the propeller.

Fig. 2 is a broken, plan view of the propeller.

Fig. 3 is a longitudinal section, taken on line III—III of Fig. 2 and showing the operation of the control lever in full and dotted lines.

Fig. 4 is a cross section on line IV—IV of Fig. 2.

Fig. 5 is a cross section on line V—V of Fig. 2.

Fig. 6 is a detail perspective view of one of a pair of cams employed in carrying out the invention.

Referring now in detail to the various parts, 1 designates oppositely-disposed supporting members provided with bearings 3 in which the propeller shaft 5 is journaled.

7 designates a pair of sprocket wheels fixedly-mounted upon opposite ends of the shaft 5 to either transmit power thereto or therefrom according to the purpose for which the propeller is to be employed.

9 designates a propeller wheel which embodies a hub 10 fixed upon the shaft 5, vanes 12 radiating from said hub 10, and reciprocating valves 14 mounted upon said vanes 12.

Each vane 12 embodies a series of slats 16 spaced apart to leave intervening ports 18 for the passage of air or water as the

case may be, during a portion of each revolution of the propeller wheel 9.

Each valve 14 embodies a series of slats 20 of about the same width as the slats 16 and spaced apart to leave intervening ports 22, which coincide with the ports 18 when the valve is in open position as disclosed by Fig. 4. The slats 20 are connected at their ends by bars 24 slidably mounted in guides 26 secured to the hub 10 and the outer ends of the respective vanes 12. The slats 20 of each valve 14 are also united by a valve rod 28, slidably mounted in guides 30 fixed to opposite sides of the respective vanes 12. The opposite ends of each valve rod 28 are provided with swiveled yokes 32 in which flanged rollers 34 are journaled.

The rollers 34 are arranged to traverse a pair of cams 36 having faces 38 and 40, disposed on different planes and connected by oblique faces 42. Said cams 36 are fixedly-secured to the circular, intermediate portions 44 of a control lever 46 embodying a pair of parallel members 48 having the circular portions 44, and a pair of transverse handles 50 uniting the ends of said members 48. The circular portions 44 have hubs 52 freely mounted upon the shaft 5, so that the control lever 46 can be rocked up and down to the full and dotted line positions, Fig. 3, while said shaft 5 is rotating.

In practice, as the propeller wheel 9 rotates the rollers 34 of the valve rods 28 successively traverse the faces 38, 42 and 40 of the cams 36. While said rollers 34 are traversing the faces 38, the valves 14 are held in open position as disclosed by Fig. 4, so that their respective slats 20 will offer but minimum resistance to the element in which they are operating be it air or water, but as the rollers 34 traverse the faces 40 of the cams 36, the valves 14 are shifted to the closed position disclosed by Fig. 5, so that their respective slats 20 will exert maximum power upon the element in which they are operating.

By mounting the cams 36 upon the control lever 46, it is obvious that said cams may be rocked in either direction, and thus cause the valves 14 to open and close at any portion of each revolution of the propeller wheel 9. This feature of the invention is an important one, especially when the propeller is applied to an aeroplane, because it enables the valves to be adjusted to raise the

aeroplane directly from the ground instead of racing over the ground to attain sufficient velocity to ascend as heretofore, and after the aeroplane attains the desired elevation it may be propelled straight ahead or up and down at any desired inclination by adjusting the control lever 46 accordingly. The foregoing remarks also apply when the propeller is employed on a submarine as the same can be caused to dive or ascend or move straight ahead through proper adjustment of the control lever 46.

Owing to the construction of the propeller wheel 9 it is equally effective when rotating either in the direction of the arrow *a* or in a reverse direction, and it can operate either in a horizontal or a vertical position.

From the foregoing description it is apparent that I have produced a propeller embodying the features of advantage above enumerated, and while I have shown and described the preferred form of my invention, I reserve the right to make such changes in the construction, proportion, and arrangement of parts as properly fall within the spirit and scope of the claims.

Having thus described my invention, what I claim and desire to secure by Letters Patent, is:

30 1. In a device of the character described, a rotary member, a vane fixed to said rotary member and having a series of ports therein, a valve to open and close said ports, a

valve rod connected to said valve to actuate the same, rollers mounted at the ends of said valve rod, and means traversed by said rollers for actuating the valve rod. 35

2. In a device of the character described, a rotary member, vanes radiating from said rotary member and provided with ports, 40 valves reciprocably mounted on said vanes to open and close the ports, and oppositely-disposed cams to actuate said valves.

3. In a device of the character described, a rotary member, vanes radiating from said 45 rotary member and provided with ports, valves reciprocably mounted on said vanes to open and close the ports, oppositely-disposed cams to actuate said valves, and a control lever to adjust said cams. 50

4. In a device of the character described, a rotary member, vanes radiating from said rotary member and provided with ports, valves reciprocably mounted on said vanes to open and close the ports, guides for said 55 valves, swiveled rollers associated with opposite sides of said valves to actuate the same, cams traversed by said rollers, and a control lever rockable on the rotary means to adjust said cams axially. 60

In testimony whereof I affix my signature, in the presence of two witnesses.

ALBERT A. AKE.

Witnesses:

PRESTON R. AKE,
F. G. FISCHER.
